DESIGN FOR AN ARTIFICIAL LEATHER FABRIC OR SIMILAR ARTICLE

Abraham Stern, New York, N. Y.

Application February 26, 1940, Serial No. 90,501

Term of patent 3½ years

To all whom it may concern:

Be it known that I, Abraham Stern, a citizen of the United States, residing in New York city, in the county of New York and State of New York, have invented a new, original, and ornamental Design for an Artificial Leather Fabric or Similar Article, of which the following is a specification, reference being had to the accompanying drawing, forming part thereof.

The figure is a plan view of an artificial leather fabric or similar article showing my design.

The design unit is contained between the dot and dash lines, which unit is repeated in regular succession as indicated by the extension beyond the unit boundaries.

I claim:

The ornamental design for an artificial leather fabric or similar article, substantially as shown and described.

ABRAHAM STERN.
